Patent expires March 9, 1964

5 Claims. (Cl. 179—1)

1

In an effort to simplify greatly the apparatus used at each station in duplex systems for loud traffic and especially to make it independent of net work connections, it had been hitherto usual to feed the amplifying valves from a central supply source over two lines each containing twin cables. All projects exploited up to the present day have been constructed for the use of direct current supply. The solution however is inefficient on account of the anode potential requirements of the amplifier being too high with respect to the standard tension authorized over long distant lines, on the one hand, and on account of the correct heating potential only being able to be obtained through resistances which obviously incur a potential drop, which in addition must be compensated for by the use of further resistances entailing still further working losses, on the other hand.

This disadvantage can be avoided to a great extent by the use of alternating current mains in place of direct current mains. In this way it is possible to furnish the sets at each station from mains at the required potential of the valves over a twin cable line at a tension quite independent of these requirements, the line tension not exceeding the voltage authorized for long-distant lines: this owing to the possibility of transforming the alternating current supply at the station mains to anode potential requirements.

This manner of feeding does away with all potential losses due to resistances in the anode and cathode circuits in the case of direct current supply.

The switching arrangement according to the invention for duplex systems for loud traffic with twin cable lines from a central supply to amplifiers at each station, respectively, is characterized in that the supply current to the amplifiers over the twin cable connecting lines is alternating at a frequency differing sensibly from the voice-frequency.

In order to avoid any risk of induction in the amplifier circuit by the supply current or, vice versa, of induction in the supply current circuit by the amplifier current, the switching is provided with independent line and supply transformers in such a manner that the effects of the supply current in the first, of the voice-current in the second are completely annulled within the respective apparatus. The same end may be attained by providing filters in the amplifier

2

and supply circuits, respectively, arranged in such a manner as to let through voice-frequency currents in the amplifier circuit, whereas the supply filter is completely impervious to the same frequency range. Moreover, a still further arrangement could be devised: By combining the effect of a transformer in one line and a filter in the other, i. e., by replacing one or the other of the transformers in the described transformer arrangement above by a frequency filter.

The drawing represents diagrammatically, and by way of example, a switching arrangement according to the invention.

S denotes a central electric supply unit, TS a subscriber's set. The second set TS¹ is not shown, being similar in construction to TS. TS and TS¹ are connected to a, b and a¹, b¹, respectively. The supply unit consists of a transformer TR connected on the one side to an alternating current supply main which can be interrupted by a switch r. The other side is connected to the outgoing supply lines at the subscribers' sets. The transformer winding is tapped in the middle and connected to earth on the one side of the tapping according to alternating-current requirements through a condenser k, on the other side, through a time-delay relay in series with a source of direct current B. a, b denote the terminals on the subscriber's set TS and on the supply unit S of the line, a¹, b¹ representing the same disposition with respect to the non-illustrated line and set TS¹.

The subscriber's station consists of a line-transformer LU, a supply current circuit and amplifier circuit.

Both terminals a, b at the station are connected to the oppositely wound primary coils of the line-transformer LU. The two secondary coils of the line-transformer lead over the grid and anode transformer primary windings to the amplifying valve V, respectively.

The supply current circuit is made up of a transformer ST, the primary winding of which is tapped in the middle, the tapping being earthed on the one hand, through a relay W in series with a condenser c according to alternating current requirements, on the other hand, directly over a key T which is open when in normal position. The secondary side of the supply current transformer ST is tapped in such a manner so as to permit the connection to conduct the current directly over rectifiers to the anode and cathode of the amplifying valve V.

The amplifier circuit consists of an amplifying valve V, a grid transformer EV, and an anode transformer AT which, dependent on the direction of transmission is connected over the two directional switches w_1 and w_2 to the line-transformer LU or to the voice-current transformer LM.

The drawing illustrates the normal switching position.

Both subscribers' stations are switched according to the diagram for receiving (corresponding positions of the switches w_1 and w_2) and the electro-acoustic transformer LM is in loud speaker working position, the contact r in the electric supply unit being open.

Let us say the subscriber at TS wants to call the station TS₁; all he has to do is to press the key T and hold it down. As a result the circuit, composed of the two sides of the secondary coil of transformer TR, the two lines a , b , the line-transformer LU, both sides of the primary coil of the supply-transformer ST and the closed key T, is fed by a direct current source B. Relay R is energised and controls in its turn its contact r which closes the alternating current circuit formed by the supply-source so that alternating voltage is induced on the subscriber side of the supply transformer. The voltage is again transformed and converted at the subscribers' stations to correspond to the required electric conditions of the anode and cathode of the amplifying valves. In this way the key T sets up connections of the amplifying sets in both stations making them ready for operation.

The aforementioned alternating current has a still further effect. The key T at station TS₁ being open, relay W₁ which corresponds to W at TS, is energised, controlling the contacts w_1 and w_2 . TS₁ is ready for transmission.

The primary coils of the line-transformer LU being oppositely wound, the leads parallel, the induced effects neutralize one another and in this way the secondary coils are freed from supply interference. However, a frequency filter is provided at F for security's sake, i. e., between the secondary side of the said transformer and the grid-transformer Eu, thus impeding leakage of any currents in this circuit other than the voice-currents. In the same manner, the voice-current is freed from supply-current interference by arranging the split primary winding so that the current flowing through one part is opposite in direction to the current flowing through the other.

This special arrangement of the supply and voice-current transformers could be replaced by two filter arrangements, one of which gives free passage to voice-current-frequencies, whereas the other impedes them. Should the first of these filter arrangements be connected in the amplifier circuit, the other in the supply circuit, there could be no danger of mutual interference between the two circuits. In a similar way the same end may be attained by combining or the supply transformer arrangement described above with a filter in the line circuit or else the line transformer arrangement described above with a filter in the supply circuit. It is thus possible in different ways to separate completely the supply and line currents.

Should it be desired to change the direction of transmission, it is only necessary for the calling subscriber to let go the key T during a small interval of time. To this end the key is provided with a time regulating device. On interruption

the direct current circuit is opened thus deenergising relay R which operates after a small lapse of time only. On the other hand relay W is no longer short-circuited, so that during the operating period of relay R, it controls the switches w_1 and w_2 . At conclusion of the time delay, the contact r opens and interrupts the alternating current supply and the set is dead. It is clear that on opening the key T the calling set TS has

10 been switched over to the transmitting position and the supply current cut off. At conclusion of the short interruption which should correspond to the lapse of time between the deenergisation of relay R and its operation, should the key be 15 now pressed down once more, then in addition to the closing of the supply source circuit, W₁ at TS₁ is energised controlling in its turn the changing over to receiving position of the switching apparatus. The direction of transmission has 20 been changed: The operation can be indefinitely repeated at will.

At conclusion of the conversation the key T of calling set TS is let go and left open so that the supply current is again interrupted in the manner already described. Further the supply 25 transformer is fitted up with a device so as to bring the switching apparatus w_1 and w_2 at conclusion of the conversation back to its normal "receiving" position, in the case of it not being already so.

It is moreover possible to arrange the supply source in such a manner so as to make it possible for the change over operation to be done as before by means of the key T at the called set.

30 Should the supply source be used in connection with an automatic central exchange, controlled by selectors and relays, any number of subscribers can be looped in. In this case the key T is replaced by a dial switch.

40 What I claim is:

1. In an installation, an alternating voice current line, a duplex system comprising, a central supply unit for supplying alternating current with another frequency than the voice current in 45 said line, a subscriber's station connected to said line, a two-wire connection between said central supply and said subscriber's station, and a loud-speaker-amplifier arranged in said subscriber's station to be fed through said two-wire connection from said central supply.

50 2. In an installation according to claim 1, a line transformer in connection with said central supply unit, and a supply transformer in connection with said voice current line, said transformers being arranged so that said line transformer is traversed by the supply current and said supply transformer by the voice current in such a way that the effects of these currents are 55 annulled within said transformers.

60 3. In an installation according to claim 1, an amplifier circuit comprising said loudspeaker amplifier, a supply circuit comprising said central supply unit, first filters in said amplifier circuit with a permeability limited to the voice frequency range, and second filters in said supply circuit, 65 impervious to the voice frequency range.

70 4. In an installation according to claim 1, a line transformer in connection with said central supply unit in such a way that the effects of the supply current within said line transformer are 75 annulled, a supply circuit comprising said central supply unit, and filters in said supply circuit, impervious to the voice frequency range.

5. In an installation according to claim 1, a supply transformer in such a connection with

said voice current line that the effects of the voice current traversing said supply transformer are annulled within the latter, an amplifier circuit comprising said loudspeaker-amplifier, filters in said amplifier circuit with a permeability limited to the voice frequency range.
